UNITED STATES PATENT OFFICE.

JAMES A. DONALDSON, OF GREENVILLE, PENNSYLVANIA.

HORSE-DETACHER.

SPECIFICATION forming part of Letters Patent No. 726,881, dated May 5, 1903.

Application filed January 19, 1903. Serial No. 139,657. (No model.)

To all whom it may concern:

Be it known that I, JAMES A. DONALDSON, a citizen of the United States, residing at Greenville, in the county of Mercer and State of Pennsylvania, have invented certain new and useful Improvements in Horse-Detachers; and I do hereby declare the following to be a full, clear, and exact description of the invention, such as will enable others skilled in the art to which it appertains to make and use the same.

This invention is an improvement upon the horse-detaching device illustrated and described in United States Letters Patent No. 594,334, issued to me November 23, 1897.

My patented device consists, broadly, of a singletree comprising two members or sections hinged to a central union or journal-piece attached to the cross-bar or other part of the vehicle, said members being held normally rigid with the union by a catch, but adapted to be released by disengaging the catch to permit said members to swing inwardly and forwardly, whereby the traces will pull off the ends of the singletree to permit immediate detaching of the horse from the vehicle. Such a device is obviously exceedingly useful in case of runaways or other accidents, as well as when it is desired to detach the horse quickly for transfer to another vehicle or on account of rain or for other causes.

The principal objects of the present invention are to produce a more efficient device of this character and to strengthen and improve the construction of the union, its pivotal connections with the opposite members of the singletree, its catch, and the device for mounting the union on the cross-bar so as to permit the singletree to oscillate thereon. These and other objects are attained by means substantially as illustrated in the accompanying drawings, which are to be taken as a part hereof, and in which—

Figure 1 is a central horizontal section through the union and adjacent ends of the two members of the singletree hinged thereto. Fig. 2 is a central transverse vertical section through the union. Fig. 3 is a bottom plan view of the same. Fig. 4 is a rear elevation thereof with the catch removed. Fig. 5 is a detail front view of the catch. Fig. 6 is a detail top view of the bearing or socket for the union. Fig. 7 is a diagrammatic plan

view of the shafts of a vehicle, with the singletree mounted on the cross-bar thereof, showing the traces and breeching in place and indicating in dotted lines the manner of detaching the latter.

The letter A (referring to Fig. 7) denotes the shafts of a vehicle; B, the usual cross-bar thereof, to which the singletree or whiffletree is attached; C, the traces, connected at their rear ends to the singletree, and D the breeching or holdback, connected to the shafts.

The singletree (designated by the letter E) comprises two members hinged or pivoted at their inner or adjacent ends to a union or journal-piece G in such manner that said members can be folded together forwardly or inwardly. Preferably the inner ends of the singletree are fitted in metal socket-pieces F, which latter are connected to the union, also of metal.

In my aforesaid patented device, as disclosed in said Letters Patent, the union consists of a T-shaped piece, to the front opposite lugs of which the singletree members, or rather their socket-pieces, are hinged, the inner ends of said members or socket-pieces abutting the opposite sides of said union and the members being held normally rigid with the union by means of a rearward spring-actuated catch having lips engaging projections on said members or their socket-pieces. The catch has a bolt or other headed stem projecting therefrom into a recess in the union, and a stout coiled spring encircles said bolt or stem, between the head thereof and a shoulder in the recess, thus holding the catch forward. The bottom of the union has a suitable bearing plate or surface fitting a bearing or socket thereon on the cross-bar, and a depending bolt or stem integral or rigid with the union or its bottom plate is inserted through an aperture in the cross-bar and secured by a clevis, nuts, or otherwise.

In my present device the union consists of a short upright piece or body having forwardly-projecting lugs g at its top and bottom, said lugs preferably extending as flanges beyond the sides of said body. The inner ends of the socket-pieces F abut flush against the opposite sides of said union, between the top and bottom flanges thereof, and said

socket-pieces are formed with pivot-lugs f , which extend between the lugs g , directly in front of the body of the union, and a suitable pin or bolt H is inserted through registering apertures in the lugs g and lugs f . As shown, one socket-piece has two of such lugs f , leaving an intermediate space to receive a single one of such lugs on the other socket-piece. It will thus be seen that such construction is simpler, stronger, and more compact, the union is more narrow, the socket-pieces F are pivoted by a single pin or bolt instead of two, which bolt lies directly in front of the center of the union, and when the members of the singletree are folded they can be brought close together for their entire lengths, since the fronts of the socket-pieces can be brought into contact.

The catch (herein designated by the letter J) is somewhat similar to that shown in my aforesaid patent, having beveled or inclined lips j at its ends fitting in similarly-formed recesses j' in the back faces of the socket-pieces F and engaging shoulders or lugs f^2 thereon to hold said socket-pieces rigid with the union, in proper position to permit pulling the vehicle by the singletree. Owing to the slight width of the union, the lugs or shoulders f^2 can be made wider, and hence stronger, than in my aforesaid patented device without increasing the length of the catch J . As shown in Figs. 4 and 5, the edges of the lips j are stepped, as shown at J' , and the edges of the shoulders or lugs f^2 are correspondingly formed, such construction being not essential, but preferable, to form a better and a stronger lock-joint and adapt the catch to snap into place, as well as to detach more readily. The catch has a central aperture j^2 , preferably angular or polygonal, which fits over a similarly-formed stud g' , projecting from the rear of the union, and a stout coiled compression-spring K incloses said stud, said spring being interposed between the back of the catch and a suitable pin k or other projection on the stud, thus holding the catch positively in place. The catch may have a sleeve j^3 thereon inclosing said stud and spring, on which a cap L may be screwed or fitted to house the spring. The catch may also be provided with a loop or pull-piece M for connection to a strap, which the driver can pull to disengage the catch from the socket-pieces, and thus permit the singletree to double up and let the ends of the traces pull off the same. By locating the spring behind the catch in the manner stated the necessity of an aperture therefor in the union, which renders the latter weaker, is thus avoided. A further advantage is attained by this location of the spring in addition to that just noted. The construction permits of a vertical bolt N being inserted clear through the union for connection to the cross-piece, which is of course impossible where the union contains a spring. Furthermore, should the bolt become worn, bent, or broken it can readily

be removed, repaired, or replaced by another one by any blacksmith, thus obviating the necessity of procuring a new union.

The union has a bearing on its under side, preferably cast integrally therewith, said bearing consisting, preferably, of a flat circular part g^2 , with one or more depending annular ribs or ledges g^3 , adapted to fit in a corresponding annular groove or grooves o in a bearing-piece O , attached to the cross-bar B , which bearing-piece O may be formed with suitable side lugs or projections having apertures to receive screws for such attachment. The bolt N passes through a tubular part g^4 in said bearing, which fits in the central opening o' in said bearing-piece. As a means for limiting the oscillatory movements of the singletree I preferably employ a pair of studs g^5 , projecting from the annular ledge g^3 into short segmental slots o^2 in the bottom of the bearing-piece O . It will thus be observed that a neat practically dust-proof bearing is produced, and the studs g^5 and slots o^2 are completely incased, and thus kept from becoming clogged by dirt and dust, so that free oscillatory movement of the singletree within the limit allowed by the travel of the studs in the slots is always insured.

The breeching or holdback may be secured to suitable devices on the shafts to permit detachment or release of said holdback when the traces are detached or the singletree doubles up.

I thus provide a very simple, strong, and efficient device, and its use and operation will be apparent from the foregoing description. As already explained, when the horse is harnessed to the vehicle the singletree is held rigid by the catch J , the ends of the traces are looped over the ends of said singletree, and the ends of the breeching-strap are suitably attached to the shafts. When it is desired to detach the horse quickly, the driver pulls back the catch by a strap connected thereto or to the pull-piece M , whereupon as the horse proceeds the two members of the singletree fold together forwardly, thus allowing the traces to pull off their ends and the breeching-strap detaches from the shafts, all as indicated by dotted lines in Fig. 7.

While the invention is shown applied to a singletree, it is obvious, of course, that it is equally applicable to doubletrees or triple-trees, &c.

Having thus fully described my invention, what I claim as new, and desire to secure by Letters Patent of the United States, is—

1. In a horse-detacher, a singletree comprising two hinged members and an intermediate union adapted to be mounted on the cross-bar or other part of the vehicle, the inner or adjacent ends of said members abutting opposite sides of said union and being hinged to the front thereof by a single pivot-pin, together with a catch normally maintaining said members rigid with the union but adapted to be disengaged and thus allow them to

fold together forwardly to permit the traces to slip off their ends, substantially as described.

2. In a horse-detacher, a singletree comprising two hinged members and an intermediate union adapted to be mounted on the cross-bar or other part of the vehicle, said union consisting of a short upright piece having a pair of forwardly-projecting lugs, the inner or adjacent ends of said members abutting the sides of said union and having pivot-lugs lying between said lugs on the union, and a pivot-pin inserted through all of said lugs, together with a catch normally holding said members rigid with the union but adapted to be disengaged to permit said members to fold together forwardly, substantially as described.
3. In a horse-detacher, a singletree comprising two hinged members and an intermediate union adapted to be mounted on the cross-bar or other part of the vehicle, said union consisting of a short upright piece having top and bottom forwardly-projecting lugs which extend as flanges beyond the sides thereof, the inner or adjacent ends of said members abutting the opposite sides of said union and being embraced by said side flanges and having pivot-lugs embraced between said front lugs and pivoted thereto by a single pivot-pin, together with a catch normally holding said members rigid with the union but adapted to be disengaged to permit them to fold together forwardly, substantially as described.
4. In a horse-detacher, a singletree comprising two members hinged to an intermediate union which is adapted to be mounted on the cross-bar or other part of the vehicle, and a spring-actuated catch located behind the union having lips which lie in recesses in the backs of said members and which engage the shoulders at the inner ends of said recesses to hold the members rigid with the union, the edges of said lips being stepped substantially as shown and the edges of said shoulders engaged thereby being correspondingly stepped.
5. In a horse-detacher, a singletree comprising two members hinged to an intermediate union or journal-piece, and a catch located

behind said union having lips which engage shoulders or projections on the backs of said members to hold them rigid with said union, a stud projecting from the union through an aperture in said catch, and a coiled compression-spring encircling said stud interposed between the catch and a suitable stop on the stud, substantially as described. 55

6. In a horse-detacher, a singletree comprising two members hinged to an intermediate union or journal-piece, and a catch located behind said union having lips which engage shoulders or projections on the backs of said members to hold them rigid with said union, a stud projecting from the union through an aperture in said catch, and a coiled compression-spring encircling said stud interposed between the catch and a suitable stop on the stud, a tubular part on the union inclosing said stud and spring, and a cap fitting said tubular part, substantially as described. 60

7. In a horse-detacher, a singletree comprising two members hinged to an intermediate union mounted on the cross-bar or other part of the vehicle, a pin or bolt inserted through said union and fastening the same to said cross-bar or other part, and a catch connecting said members behind the union and holding them rigid therewith, said catch being held in place by a spring located behind the same, substantially as described. 75

8. In a horse-detacher, the combination of a singletree comprising two members hinged to an intermediate union, said union having a bottom bearing with an annular depending ledge, a bearing on the cross-bar or other part of the vehicle on which said first-mentioned bearing is fitted, the second bearing having an annular groove to receive said annular ledge, and a depending stud or studs on said 80 annular ledge projecting into a short slot or slots in the bottom of said annular groove, to permit a limited oscillatory movement of the singletree, substantially as described. 85

In testimony whereof I affix my signature in presence of two witnesses.
